UNITED STATES PATENT OFFICE.

ELLSWORTH E. QUAINTE, OF DENVER, COLORADO, ASSIGNOR TO THE QUAINTE MANUFACTURING COMPANY, OF DENVER, COLORADO, A CORPORATION OF COLORADO.

PERMUTATION-LOCK FOR SAFES.

1,376,638.

Specification of Letters Patent.

Patented May 3, 1921.

Application filed July 17, 1919. Serial No. 311,539.

To all whom it may concern:

Be it known that I, ELLSWORTH E. QUAINTE, a citizen of the United States, residing at the city and county of Denver 5 and State of Colorado, have invented certain new and useful Improvements in Permutation-Locks for Safes; and I do declare the following to be a full, clear, and exact description of the invention, such as will 10 enable others skilled in the art to which it appertains to make and use the same, reference being had to the accompanying drawings, and to the characters of reference marked thereon, which form a part of this 15 specification.

My invention relates to improvements in locks, more especially adapted for use in connection with the doors of safes and vaults, my object being to provide an efficient and secure lock of this character, which shall at the same time be comparatively simple in construction and economical in cost.

The framework of the lock is circular in front and rear view, its outermost plate being the largest, the said framework being stepped inwardly toward the axis of the door from the outer to the inner plate, as is customary in vault and large safe doors.

Mounted within the inner portion of the 30 framework is the lock mechanism proper, consisting of a cylindrical structure comprising a hollow core, upon which are mounted a number of tumblers independently adjustable, and each containing an 35 outer adjustable body member carrying a numbered disk which is adjustable within the body of the tumbler for the purpose of changing the combination; and a second disk which, while removable, is permanently 40 positioned in the tumbler and is provided with recesses adapted to engage a click ball which is spring actuated and can be felt or heard by the operator as he turns the tumbler a predetermined distance, or the distance 45 between two recesses of the second disk. A spacing member is arranged between the second disks of each two tumblers, and carries two click balls which, as illustrated in the drawing, are normally 50 forced outwardly into engagement with the recesses of the second disks by a common spiral spring, the click balls protruding sufficiently through perforations in adjacent 55 parts of the spacing member to engage the recesses of the said disks. The perforations,

however, are of such size as to prevent the balls from passing through. Any desired number of tumblers may be employed. The body member of each tumbler has an inwardly projecting collar, which is slotted 60 or toothed to engage the edge of a pallet member, which is mounted in the hollow core of the tumbler mechanism and provided with parts projecting beyond the same whereby the pallet member is adjustable vertically from the outside. Normally this pallet member is disengaged from the slots or recesses of the body of the tumbler and it works in conjunction with a second pallet member of similar construction but which 65 is so shaped as to enter a recess or slot formed in the numbered disks, also of the tumblers when the combination of the lock is solved or when the recesses of all the numbered disks are in longitudinal alignment. 70

Before solving the combination, the first named pallet member may be moved a short distance, whereby it is caused to engage the aforesaid slots or recesses of the bodies of 80 all of the tumblers, and when so adjusted, locks the tumbler members against rotation. The construction for adjusting the two pallet members is of such character that the first pallet member is first actuated to engage the slots of the bodies of the tumblers and if the combination is solved the second pallet member will, by the same operation, its movement however, being slightly later, engage the slots or recesses of the numbered 90 disks. When this occurs, the second pallet member is in such position that a rod accessible from the outside may be adjusted longitudinally to permit the rotation of an operating spindle which adjusts a relatively 95 large disk located within the framework of the door and which is so connected with locking bolts that the latter may be withdrawn from the portion of the safe surrounding the door, whereby the latter is free 100 to open. The tumblers of the lock mechanism are rotatably adjusted from the outside through the medium of a series of spindles whose inner extremities carry pinions which engage gears formed on the bodies of 105 the tumblers. The second pallet member has a part detachable from the inside of the safe or vault, so that the door can not be opened from the outside even when the combination of the lock is solved, thus enabling a 110

bank official to enter the vault, close the door, and prevent a robber from gaining access to the vault.

Having briefly outlined my improvement, 5 I will proceed to describe the same in detail, reference being made to the accompanying drawing, in which is illustrated an embodiment thereof. In this drawing:

Figure 1 is a fragmentary, front view of 10 a safe or vault provided with a door equipped with my improved lock mechanism.

Fig. 2 is a horizontal section taken 15 through the door on the line 2—2, Fig. 1.

Fig. 3 is a rear view of a safe door 20 equipped with the lock, a portion of the casing being removed to disclose the tumbler mechanism in elevation.

Fig. 4 is a vertical section taken on the 25 line 4—4, Fig. 3, showing the lock mechanism in the locked position.

Fig. 5 is a view illustrating the tumbler mechanism and the two pallet members, 30 shown in the locked position and looking into the cup-shaped body of the tumbler with both disks removed.

Fig. 6 is a similar view with the numbered disk in place.

Fig. 7 is a similar view with the second 35 disk in place, or that which co-operates with the click ball as the tumblers are rotatably adjusted.

Fig. 8 is a section taken through the lock on the line 8—8, Fig. 4, looking toward the 40 left.

Fig. 9 is a section taken approximately on the line 9—9, Fig. 4, looking toward the right.

Fig. 10 is a vertical, longitudinal section 45 of the hollow core of the locked mechanism.

Fig. 11 is an end view of the same.

Figs. 12 and 13 show respectively the opposite end members applied to the core of the lock mechanism beyond the tumblers.

Figs. 14, 15, 16 and 17 are views substantially the same as Figs. 4, 5, 6 and 7, but showing the lock mechanism in the unlocked position.

Fig. 18 is a view substantially the same 50 as Fig. 8, but showing the mechanism in the unlocked, as distinguished from the locked, position.

Fig. 19 is a view illustrating the tumbler mechanism in longitudinal section with both 55 pallet members in place.

Figs. 20 and 21 respectively illustrate the two pallet members in face view.

Fig. 22 shows fragmentary end elevations 60 of the respective pallet members illustrated in Figs. 20 and 21.

Fig. 23 is a view of Fig. 20, looking in the direction of arrow 23.

Fig. 24 is a rear view of the detachable part of one of the pallet members.

Fig. 25 is an edge view.

Fig. 26 is an underneath view of the same.

Fig. 27 is a vertical, longitudinal section, taken through the tumbler mechanism and its casing with the pallet members and the central core removed, shown on a larger 70 scale than in the other views.

Fig. 28 is a detail view of the cup-shaped body member of a tumbler looking thereinto with both disks removed.

Fig. 29 is an end elevation of a ring spacing the slotted flange of the tumbler body from the numbered disk. 75

Fig. 30 is a face view of the numbered disk.

Fig. 31 is a similar view of the disk which 80 engages a click ball.

Figs. 32 and 33 are side and edge views, respectively, of a spacing member extending into the cup-shaped body members of two tumblers and carrying the click balls 85 which engage the corresponding disks of the two tumblers.

Fig. 34 is a view of one of the centrally located cup-shaped members surrounding the core and spacing the two sets of tumblers on opposite sides. 90

The same reference characters indicate the same parts in all the views.

Let the numeral 5 designate the circular framework of a safe or vault door, having 95 an outer plate 6, an inner plate 7, and an intermediate plate 8, dividing the cavity of the framework into front and rear compartments 9 and 10. The outer circular portion of the casing between the plates 6 and 7 is 100 stepped, as shown at 12, as is customary in structures of this character. Within the forward compartment 9 is located a rotatable disk 13, which is journaled upon a central sleeve 14, having an exteriorly projecting circumferential flange 15, which engages the intermediate plate 8. The disk 13 is engaged by a second sleeve 16, having an interiorly projecting flange 17, which engages the outer edge of the sleeve 14. The disk 13 is provided with a number of curved slots 18, which are engaged by pins 19 connected with bolts 20, which are shiftable outwardly and inwardly by the movement of the disk 13 in the proper directions, the slots being 110 out of line with arcs struck from the center of the disk. The disk 13 is given the necessary partial rotary movement in reverse directions through the medium of a segmental gear 21, formed on the outer face of the disk and co-operating with a pinion 22, 115 fast on a spindle 23, which is journaled in the door casing and provided at its outer exposed extremity with a convenient hand hold 24. When the combination of the lock 120 is solved and the pallet members 25 and 26 are properly adjusted, a rod 27 may be moved longitudinally to the position shown in Fig. 14, after which the disk 13 may be moved for the purpose of shifting the bolts 130

20 to the unlocked position, all as herein-after more fully explained.

The tumbler mechanism of the lock and the manner of operating the same, will now 5 be described.

This mechanism is inclosed in a casing 28, inserted in an opening formed in the rear plate 7 of the door, said casing extending through the compartment 10 and abutting 10 against the rear surface of the plate 8. This casing projects inwardly beyond the plate 7 and is closed on the inside by a removable plate 29, for convenience in removing the tumbler mechanism for the purpose of 15 changing the combination, or when for any reason such removal may be necessary. This casing 28 must be rigidly secured in place upon the door, and this may be accomplished in any suitable manner. Within the casing 20 28 the tumbler mechanism may be inserted in its entirety when the pallet members are in position, inasmuch as the top and bottom walls of the casing 28 are slotted to receive the vertically projecting parts of the pallet 25 members, as hereinafter more fully described.

The tumbler mechanism consists of a central core 30 (see Fig. 10), which is provided with a long longitudinally disposed slot 4 30 at the top, and a relatively narrow slot 31 at the bottom, the last named slot being provided to accommodate the lower vertical projections 32 and 33 of the respective pallet members 25 and 26. Within this core, which 35 is hollow, are located the parts 34 of the pallet member 25, which extend at right angles in opposite directions from the vertical parts; and the similar parts 35, which extend in opposite directions from the vertical 40 parts of the member 26. The parts 34 of the pallet member 25 are provided with four upwardly projecting parts 36, which are adapted to respectively enter recesses 37, formed in the inwardly projecting flanges 45 38 of the four tumblers 39. The lower part 32 of the pallet member 25 passes through the slot 31 of the core, and also through an opening 41 in the bottom of the casing, while its upper vertical part 40 passes through the 50 slot 4 of the core and an opening 42 in the top of the casing. These openings 41 and 42 of the casing extend rearwardly through the respective parts of the casing and are open until the rear plate 29 is put in place, thus 55 making it practicable to introduce the entire tumbler mechanism with the pallets in place into the casing 28 when the rear plate is removed, as heretofore explained.

The parts 35 of the pallet 26 are cut away 60 in four places, as shown at 43, to make room for the parts 36 of the pallet 25, so that the two pallets may be in actual contact but independently movable, the parts 36 being laterally offset from the parts 34 of the pallet 65 25, as best illustrated in Fig. 23. Further-

more, the parts 35 of the pallet 26 are provided with parts 44, which are adapted to enter recesses 45 formed in the several numbered disks 46 of the several tumblers. These parts 44 are so located and arranged 70 that they can only engage the slots 45 of the disks 46 when these disks are all so positioned that the recesses 45 are in longitudinal alinement; and when this is the case the combination is solved. 75

Each disk 46 is numbered from "0" to "20," whereby it may be given twenty-one different positions in its tumbler member, and every change of position changes the 80 combination of the lock.

There is a series of recesses 47 in the outer edge of each disk 46, the various recesses 47 being positioned to correspond with the respective characters of the disk. The cup-shaped body member 39 of each tumbler contains a slight inward projection or tongue 48, adapted to enter any recess 47 of the disk 46. Hence, in inserting the disk 46 in the cup-shaped member 39, it may be so positioned that any one of its characters, 85 from "0" to "20," will be opposite the tongue 48 of the body member of the tumbler and the necessary adjustment in order to solve the combination will depend upon the positions of the various disks 46 in their respective tumbler members 39. The recesses 45 of the disks 46 are always in alinement with one of the recesses 37 of the body member of the tumbler, and with a recess 49^a of a disk 49, which is inserted in the tumbler member 100 after the disk 46 is put in place.

The positioning of the disks 46 and 49 in each tumbler member may be readily understood by reference to Fig. 27.

As shown in the drawing, the disk 46 is 105 spaced from the slotted flange 38 of the tumbler member 39 by a ring 50. This, however, is not particularly important and may be employed or not, as desired.

Assuming that the spacing ring 50 and 110 the two disks 46 and 49 are inserted in each tumbler member and that there are four tumblers in the lock mechanism, as illustrated in the drawing, and that these members are arranged on opposite sides of the 115 central portion of the tumbler mechanism, and that the open extremities of each pair of tumblers 39 are turned toward each other, as well illustrated in Fig. 27, a spacing member 51 is mounted on the core and 120 projects into the open ends of the two tumbler members outside of the core. Each of these spacing members 51 is provided with two projections 52 between which is located a sleeve 53, in which is arranged a spiral 125 spring 54, which acts at its opposite extremities on balls 55, which extend partially through openings 56, formed in the projections 52. The spring 54 is under compression between the two balls and normally 130

forces said balls outwardly to their limit of movement. These balls are positioned to engage the recesses 49^a of the two disks 49 of the corresponding pair of tumblers. 5 Hence, as any tumbler is rotated, the number of spaces is determined, either audibly or through the sense of feeling, since every movement of a tumbler member rotatably upon the core for a distance equal to that between two of the recesses 49^a of a disk 49, 10 will cause the adjacent ball 55 to be pressed inwardly against its spring until the next recess is reached, when the ball will move outwardly into said recess a short distance, 15 producing either a click, or at least a slight jar, which is noticeable by the operator through the sense of feeling.

The spacing member 51, arranged between each pair of tumblers, is so fixed upon the 20 core that a slot 57, formed therein, registers with the slot 4 of the core, this slot 57 making it practicable for the parts 44 of the pallet member 26 to move upwardly into engagement with the several recesses 45 of the 25 numbered disks and the registering recesses 49^a of the disks 49, when the combination is solved.

Applied to the central portion of the core 30 are two abutting sleeves 58, which have 30 inwardly extending flanges 59, which respectively engage the adjacent flanges 38 of the adjacent tumbler members 39. These sleeves are slotted at the top and bottom, as shown at 60 and 61, to receive the upper and lower 35 vertical parts of the two pallet members 25 and 26. These slots 60 and 61 register with the slots 4 and 31 of the core 30, and with the openings 41 and 42 of the casing. The tumbler members are securely clamped upon 40 the core through the medium of two heads 62 and 63, which are centrally chambered as shown at 64 to receive the opposite ends of the core, the portions of the heads around the central cavities abutting against the adjacent tumbler members 39, these heads being 45 adjustable by means of set screws 65, threaded into the opposite ends of the casing 28 and centrally engaging the respective heads. By adjusting these screws, the tumblers are properly adjusted lengthwise of 50 the core, so that while they may be turned freely thereon, they will not be too loose.

Each tumbler is provided with a relatively large exteriorly projecting bevel gear 55 66, the several gears 66 respectively meshing with pinions 67, fast on the inner extremities of spindles 68, whose outer extremities are provided with knobs 69, for convenience of adjustment. By virtue of this 60 construction, a person who knows the combination may readily adjust the tumblers to solve the combination by the manipulation of the knobs 69. The upper vertical part 40 of the pallet member 25 is provided with 65 an opening 70, vertically elongated, while

above and below said opening are flanges 71 and 72, adapted to engage a cam 73, mounted on a spindle 74, the cam being of the eccentric type and so arranged that when in a predetermined position of rotary adjustment 70 it will lift the pallet 25 and cause the projections 36 to engage the recesses 37 of the various tumbler members 39. The spindle 74 is journaled in the plates 6, 7 and 8, of the door and extends entirely therethrough, 75 its outer extremity having a knob 75 to facilitate manipulation. This spindle may be turned at any time, even when the mechanism is in the locked position, sufficiently to lift the projections 36 of the pallet 25 into 80 engagement with the recesses 37 of the respective tumbler members 39, and when this is done, the tumblers can not be rotated or adjusted for the purpose of solving the combination. This provision is important from 85 the fact that it confuses an evilly disposed person who is endeavoring to open the lock and at the same time it is a safety provision, for, when the pallet is lifted, to cause the projections 36 to engage the tumbler members as aforesaid, the tumblers can not be moved at all. Furthermore, the upper extremity of the vertical part 33^a of the pallet member 26 is provided with a similar vertically elongated opening 76, which registers 90 with the similar opening 70 of the pallet member 25. There are also upper and lower flanges 77 and 78, formed on the part 33^a, at the opposite end of the opening 76. There is a cam 79 also mounted on the spindle 74 100 and adjacent the cam 73. These cams, however, while of the same shape, are differently positioned, as indicated in Fig. 19, in which figure the mechanism is shown with the pallets adjusted to permit the unlocking 105 of the door. The two pallets are so positioned in relation to each other that the two flanges 71 and 72 of the one pallet member project in opposite directions from the corresponding flanges 77 and 78 of the other 110 pallet member, as illustrated in Figs. 5, 6 and 7. The two cams are slightly spaced, and the portion of the spindle between the cams passes through the two registering openings 70 and 76. The function of lower portion 32 of the pallet member 25 is to accurately guide the pallet and maintain it in its proper relative position at all times, as this part passes through the slot 31 of the core 30, slot 61 of the sleeves 58 and slot 41 115 of the casing. However, the lower vertical part 33 of the pallet member 26 has a part 80 detachably connected therewith by means of a bolt 81, which passes through an opening 82, formed in the part 33, and a registering opening 84 formed in the part 80. This part 80 is slidably mounted on the inner plate 7 of the door, the part 80 having a laterally reinforced offset part 85, which is 120 grooved on opposite sides, as shown at 86, to 130

receive the edges of the plate 7 on opposite sides of a slot therein, which receives the grooved offset part 85, the part 80 being applied to the plate from above and before the casing 28 is put in place. Normally, or when the mechanism is in the locked position, the pallet member 26 and part 80 connected therewith are in their lowermost position, or that illustrated in Fig. 4. The part 80 has an opening 87 whose lower part is enlarged, as shown at 88, to receive the inner extremity 89 of the rod 27, which passes through the door and is provided at its outer extremity with a knob 90. The upper part 91 of the opening 87 in the part 80 is reduced in size as compared with the part 88, but is large enough to receive a reduced part 92 of the rod 27, which is just forward of the extremity 89, this reduced part or neck 92 occupying the part 91 of the opening 87 when the mechanism is in the locked position, as shown in Fig. 4. When the combination of the tumbler mechanism is solved, the two pallet members may be raised by imparting partial rotation to the spindle 23, through the medium of the cams 73 and 79. This upward movement of the pallet member 26 lifts the part 80 and brings the part 88 of the opening 87 into horizontal alignment with the inner extremity 89 of the rod 27, and permits this rod to be moved outwardly to the position shown in Fig. 14, since the inner extremity 89 of the rod will enter the part 88 of the opening, but is too large to enter the part 91. This outward movement of the rod 27 brings a reduced part 93 of the rod 27 into alignment with a curved slot 94, formed in the movable disk 13. One extremity 95 of this slot 94 is large enough to receive the body part of the rod 27, but the latter is too large to pass through the main portion of the slot 94; hence, when the rod 27 is at its inward limit of movement, as illustrated in Fig. 4, the disk 13, which actuates the locking bolts 20, as heretofore explained, can not be moved for locking or unlocking purposes, but as soon as the rod 27 is moved outwardly to the position shown in Fig. 14, and the reduced part 93 of the rod is brought into alignment with the slot 94, the plate may be moved rotatably for unlocking the door, since the reduced part 93 is of such size as to enter the slot 94. Hence, when the rod is moved to the position shown in Fig. 14, the disk 13 may be moved from the position shown in Fig. 8 to that shown in Fig. 18 by turning the spindle 23, in which event the pinion 22 engages the segmental gear 21 for the purpose.

It should also be explained that the plate 13 is provided with a slot 96 of sufficient width to receive the spindle 23, and of sufficient length to permit the necessary movement for operating the bolts 20. Further-

more, the disk 13 is slotted as shown at 97 to receive the spindle 74, which operates the cams; as heretofore explained, this slot must be of sufficient length to permit the necessary movement of the disk 13. 70

Attention is called to the fact that the spindle 23 is also provided at its inner extremity with a hand-hold 98, whereby the disk 13 may be manipulated for locking or unlocking the door from the inside. For 75 instance, in the event that a bank official may find it necessary, in order to protect himself, and the contents of the vault, to enter the vault through the door, he may by grasping the hand-hold 98, lock the door and 80 detach the part 80 from the pallet member 26, thus making it impossible to manipulate this part by lifting the pallet 26. And as this part 80 can not be lifted, the rod 27 can not be moved outwardly to the position 85 shown in Fig. 14, and consequently the disk 13 can not be operated for the purpose of unlocking the safe from the outside. When, however, the person within the vault wishes to open the door, he may lift the part 80 into 90 position to allow the inner extremity 89 of the rod 27 to pass through the part 88 of the opening, after which he may push the rod 27 to the operative position shown in Fig. 14. Then, by operating the spindle 23 from 95 the inside, he may unlock the door and let himself out.

From the foregoing description, the use and operation of my improved lock mechanism will be readily understood. 100

If we assume that the door is locked and it is desired to open the same, a party knowing the combination would at first manipulate the tumblers through the medium of the knobs 69, the spindles 68, the pinions 67, and 105 the gears 66, as heretofore explained. When these tumblers are properly manipulated, all of the numbered disks 46 will be so adjusted as to bring the recesses 45 into alignment with the upper edge of the parts 44 of the pallet 26. Then, by operating the spindle 74, which carries the cams 73 and 79, the two pallet members 25 and 26 will be raised and the part 80, connected with the pallet member 26, will be lifted to bring 110 the part 88 of its opening 87 into alignment with the inner extremity 89 of the rod 27. This rod 27 may then be moved outwardly to the position shown in Fig. 14, whereby the reduced part 93 of the rod is brought 115 into alignment with the slot 94, permitting the disk 13 to be given a partial rotation in the direction of arrow *a*, Fig. 8, through the instrumentality of the spindle 23, the pinion 22 on the spindle, and the segmental gear 120 21 of the disk 13. This movement of the disk 13 in the direction of arrow *a* will place the last named disk in the position illustrated in Fig. 18, the bolts 20 being withdrawn from the body of the safe into the 125 130

door, by the movement of the small pins 19 with which the bolts 20 are respectively provided, in the slots 18 of the disk, these slots being slightly out of line with arcs struck 5 from the axial center of the door, this non-conformity being sufficient to impart the necessary radial movement to the bolts 20 for locking and unlocking purposes. When it is desired to lock the door, the position 10 of the disk 13 will be reversed through the instrumentality of the spindle 23 and its connections, after which the rod 27 will be moved inwardly from the position shown in Fig. 14 to the position shown in Fig. 4. The 15 pallet members may then be moved upwardly by the proper rotary movement of the spindle 74 and by virtue of the construction and arrangement of parts heretofore described. Then, by imparting a 20 partial rotary movement to one or more of the tumblers through the medium of the corresponding spindles 68 and their connections, the door will be locked and only a person who knows the combination will be 25 able to open it.

I claim:

1. The combination with a door or other suitable supporting framework, of a disk 30 rotatable therein, bolts connected with the disk to be actuated for locking and unlocking the door as the disk is rotated in reverse directions, the disk having a curved slot which is enlarged at one end, a rod movable in the enlarged extremity of the slot but 35 being too large to pass through the body of the slot, the rod having a reduced part adapted to pass through the body of the slot but out of alinement with the slot when the door is locked, the rod being longitudinally 40 movable to bring the reduced part into alinement with the body of the slot, and means, including permutation devices, for controlling the movement of said rod.

2. The combination with a door or other 45 suitable supporting framework, of a disk rotatable therein, bolts connected with the disk to be actuated for locking and unlocking the door as the disk is rotated in reverse directions, the disk having a curved slot 50 which is enlarged at one end, a rod movable in the enlarged extremity of the slot but being too large to pass through the body of the slot, the rod having a reduced part adapted to pass through the body of the slot 55 but out of alinement with the slot when the door is locked, the rod being longitudinally movable to bring the reduced part into alinement with the body of the slot, a movably mounted pallet for controlling the 60 movement of said rod, and permutation devices for controlling the movement of the pallet.

3. The combination with a door or other 55 suitable supporting framework, of a disk rotatable therein, bolts connected with the

disk to be actuated for locking and unlocking the door as the disk is rotated in reverse directions, the disk having a curved slot which is enlarged at one end, a rod movable in the enlarged extremity of the slot but 70 being too large to pass through the body of the slot, the rod having a reduced part adapted to pass through the body of the slot but out of alinement with the slot when the door is locked, the rod being longitudinally 75 movable to bring the reduced part in alinement with the body of the slot, a pallet having an opening varying in size, and the rod having adjacent parts also varying in size, the larger part of the rod being adapted to 80 pass through the larger part of the pallet opening but out of alinement therewith when the door is locked.

4. The combination with a door or other suitable supporting framework, of a disk 85 rotatable therein, bolts connected with the disk to be actuated for locking and unlocking the door as the disk is rotated in reverse directions, the disk having a curved slot which is enlarged at one end, a rod movable 90 in the enlarged extremity of the slot but being too large to pass through the body of the slot, the rod having a reduced part adapted to pass through the body of the slot but out of alinement with the slot when the door is 95 locked, the rod being longitudinally movable to bring the reduced part into alinement with the body of the slot, a pallet having an opening varying in size, the rod having adjacent parts also varying in size, the larger part of the rod being adapted to pass 100 through the larger part of the pallet opening but out of alinement therewith when the door is locked, and permutation devices for controlling the movement of the pallet to 105 bring the larger part of the pallet slot into alinement with the larger part of the rod to permit the longitudinal movement of the latter.

5. The combination with a door or other suitable framework, of a disk rotatable therein, locking bolts connected with the disk to be moved radially as the disk is rotated for locking and unlocking purposes, a longitudinally movable rod positioned in the door parallel with its axis and arranged to prevent the movement of the disk when the bolts are in the locking position, a pallet for controlling the movement of the rod, and permutation devices for controlling the 110 movement of the pallet.

6. The combination with a door or other suitable framework, of a disk rotatable therein, locking bolts connected with the disk to be moved radially as the disk is rotated for locking and unlocking purposes, a longitudinally movable rod positioned in the door parallel with its axis and arranged to prevent the movement of the disk when the bolts are in the locking position, a pallet for 115 120 125 130

controlling the movement of the rod, and having an opening varying in size, the rod also having adjacent parts varying in size, the larger part of the rod being adapted to 5 pass through the larger part of the opening, the latter being out of alinement with the corresponding part of the rod when the door is locked.

7. The combination with a door or other 10 suitable framework, of a disk rotatable therein, locking bolts connected with the disk to be moved radially as the disk is rotated for locking and unlocking purposes, a longitudinally movable rod positioned in the 15 door parallel with its axis and arranged to prevent the movement of the disk when the bolts are in the locking position, a pallet for controlling the movement of the rod, having an opening varying in size, the rod 20 also having adjacent parts varying in size, the larger part of the rod being adapted to pass through the larger part of the opening, the latter being out of alinement with the corresponding part of the rod when the door 25 is locked, and permutation devices for controlling the movement of the pallet to bring the larger part of its opening into alinement with the larger part of the rod to permit the movement of the latter to release the disk.

30 8. The combination with a door or other suitable framework, of a disk rotatable therein, locking bolts connected with the disk to be moved radially as the disk is rotated for locking and unlocking purposes, a longitudinally movable rod positioned in the door parallel with its axis and arranged to prevent the movement of the disk when the bolts are in the locking position, a pallet 35 for controlling the movement of the rod, having an opening varying in size, the rod also having adjacent parts varying in size, the larger part of the rod being adapted to pass through the larger part of the opening, the latter being out of alinement with the 40 corresponding part of the rod when the door is locked, and permutation devices for controlling the movement of the pallet to bring the larger part of its opening into alinement with the larger part of the rod to permit the movement of the latter to release the disk, the part of the pallet having the said opening being detachably connected with its body part.

45 9. The combination with a door or other suitable framework, of a disk, rotatable therein, locking bolts connected to be moved radially with reference to the disk's axis of rotation for locking and unlocking purposes, a longitudinally movable rod positioned in the door parallel with its axis and arranged to prevent the movement of the disk when the bolts are in the locking position, a pallet 50 for controlling the movement of the rod, permutation devices for controlling the movement of the pallet, and a spindle jour-

naled in the door and connected in operative relation with the disk for actuating the latter.

10. The combination with a door or other suitable framework, of a disk, rotatable 70 therein, locking bolts connected to be moved radially with reference to the disk's axis of rotation for locking and unlocking purposes, a longitudinally movable rod positioned in the door parallel with its axis and arranged 75 to prevent the movement of the disk when the bolts are in the locking position, a pallet for controlling the movement of the rod, permutation devices for controlling the movement of the pallet, and a spindle journaled in the door and connected in operative relation with the disk for actuating the latter, said spindle passing entirely through the door and being operable from both sides 80 thereof.

85 11. The combination with a door or other suitable framework, of a disk, rotatable therein, locking bolts connected to be moved radially with reference to the disk's axis of rotation for locking and unlocking purposes, 90 a longitudinally movable rod positioned in the door parallel with its axis and arranged to prevent the movement of the disk when the bolts are in the locking position, a pallet for controlling the movement of the rod, 95 permutation devices for controlling the movement of the pallet, and a spindle journaled in the door and connected in operative relation with the disk for actuating the latter, said spindle passing entirely through the 100 door and being operable from both sides thereof, the disk being slotted to receive the said spindle when the disk is rotated.

105 12. The combination with a door or other structure to be locked in a predetermined position, of a plate movable around the central axis of the door, a rod for controlling the movement of the plate, the rod being endwise movable in the door parallel with its axis, a pallet movable at right angles to the movement of the bolt for controlling the movement of the latter, and permutation devices for controlling the movement of the pallet.

110 13. The combination with a door or other structure to be locked in a predetermined position, of a plate movable around the axis of the door, a rod for controlling the movement of the plate, the rod being longitudinally movable in the door parallel with its axis, a 115 pallet movable at right angles to the movement of the bolt for controlling the movement of the latter, permutation devices for controlling the movement of the pallet, and means for manipulating the permutation devices from the outside of the door to solve the combination of the lock and permit the movement of the pallet.

120 14. The combination with a door or other structure to be locked in a predetermined po- 130

- sition, of a plate movable around the axis of the door, a rod for controlling the movement of the plate, the rod being longitudinally movable in the door parallel with its axis, 5 a pallet movable at right angles to the movement of the bolt for controlling the movement of the latter, permutation devices for controlling the movement of the pallet, means for manipulating the permutation devices from the outside of the door to solve the combination of the lock and permit the movement of the pallet, and a spindle for actuating the pallet when the combination is solved.
15. 15. The combination with a door or other structure to be locked in a predetermined position, of a plate movable around the axis of the door, a rod for controlling the movement of the plate, the rod being longitudinally movable in the door parallel with its axis, 20 a pallet movable at right angles to the movement of the bolt for controlling the movement of the latter, permutation devices for controlling the movement of the pallet, 25 means for manipulating the permutation devices from the outside of the door to solve the combination of the lock and permit the

movement of the pallet, and a spindle for actuating the pallet when the combination is solved, the last named spindle passing 30 through the door and the said disk, the latter being slotted to make room for the spindle when the disk is actuated.

16. The combination with a door or other structure to be locked in a predetermined position, a plate movable around the central axis of the door, a rod for controlling the movement of the plate, the rod being longitudinally movable in the door parallel with its axis, a pallet movable at right angles to the movement of the bolt for controlling the movement of the latter, permutation devices for controlling the movement of the pallet, means for manipulating the permutation devices to solve the combination of the lock and permit the movement of the pallet, said means comprising a plurality of spindles journaled in the door, operable from the outside thereof and connected in operative relation with the respective tumblers of the 40 45 permutation devices.

In testimony whereof I affix my signature.

ELLSWORTH E. QUAINTANCE.
